United States Patent Office

Des. 185,627
Patented July 7, 1959

185,627

ACTION TOY

Ralph W. Crawford, East Aurora, N.Y., assignor to
Fisher-Price Toys, Inc., East Aurora, N.Y.

Application January 15, 1958, Serial No. 49,260

Term of patent 14 years

(Cl. D34—15)

Fig. 1.

Fig. 2.

Fig. 3.

Fig. 4.

Fig. 1 is a top plan view of an action toy, showing my new design;

Fig. 2 is a side elevational view thereof;

Fig. 3 is a front elevational view thereof; and

Fig. 4 is a rear elevational view thereof.

The fragmentary broken line showing of a pull string is for illustrated purposes only.

I claim:

The ornamental design for an action toy, substantially as shown and described.
